UNITED STATES PATENT OFFICE.

ELMER S. STACK, OF SOMERVILLE, MASSACHUSETTS.

BALL-COCK.

1,038,014.

Specification of Letters Patent. Patented Sept. 10, 1912.

Application filed September 28, 1907, Serial No. 394,956. Renewed February 3, 1912. Serial No. 675,342.

To all whom it may concern:

Be it known that I, ELMER S. STACK, of Somerville, in the county of Middlesex and State of Massachusetts, have invented certain new and useful Improvements in Ball-Cocks, of which the following is a specification.

This invention has relation to automatic valves, and more especially to that type known as ball cocks, which control the inlet of water under pressure to a reservoir in which a supply of water is kept at a desired level.

The chief object of the invention is to keep the valve away from its seat as much as possible when admitting water and to close the inlet promptly when a sufficient quantity of water has been admitted.

The inlet valve of the style of ball cock now most commonly in use, closes as gradually as the rising of the water level in the reservoir. The chief disadvantage of such a ball cock is that, as the inlet valve approaches its seat, it is attacked by the strong head of the water for so great a period during each closing that in a comparatively short time the valve and its seat become worn and permit leakage. Another disadvantage is that a longer period of time is required to fill the reservoir since the flow from the supply pipe diminishes constantly as the water level in the reservoir rises, and the valve may possibly never be pressed so close to its seat as to completely cut off the supply. The result is a prolonged if not a continual leakage through the supply valve and the consequent wearing away thereof.

In the present invention, the disadvantage of unduly wearing away the valve is overcome by reducing the outlet of the valve casing on the discharge side of the valve, and providing what I shall hereinafter term a "differential pressure area" in the valve. Still further, the disadvantage of preventing a copious discharge into the reservoir by confining the water in the valve casing is overcome by providing a variable discharge opening which is reduced when the valve is relatively close to the valve seat, and which is increased when the valve is relatively distant from the seat. By reason of reducing the outlet of the casing, the valve, which is of greater cross-sectional area than the

inlet, is subjected to a correspondingly greater resistance from the water, and this opposes the buoyancy of the float with increased force, causing the latter to rise more slowly than if it were free. At this point, the valve is farther from its seat than would be the case if there were no back pressure in the valve casing. The valve and seat are therefore free from a rush of water past them and the consequent wear. The diminished outlet then becomes the place where the rush of water causes wear, but at that point the wear is of no consequence.

Continued rising of the float causes the valve to approach its seat, and when it approaches so close as to reduce the inlet of water to such volume as can pass through the reduced outlet without being forced, the back pressure against the valve plunger is relieved and the buoyancy of the partially submerged float causes it to rise quickly, thereby closing the valve promptly and completely against its seat. The float still remains submerged somewhat below its normal level, because its buoyancy is finally opposed by the stopping of the valve by the valve-seat. It will be understood, therefore, that, when the valve is finally closed, there is still an excess of buoyancy of the float to keep the former closed so long as the water level does not fall. In a ball cock, in which there is no back pressure to oppose the rise of the float, the valve, when closed, if indeed it ever becomes completely closed, is balanced between the pressure of water on one side and the buoyancy of the float on the other, and its liability to a constant leakage and consequent wear is apparent especially if the pressure of the water fluctuates. In the reverse operation of the ball cock, that is when the water level falls by reason of a discharge from the reservoir, the inlet valve does not open simultaneously with the fall of the water level. The valve, in fact, remains closed until the buoyancy of the float is diminished to such a degree as to be overcome by the pressure of water in the comparatively small area of the inlet. The valve then opens, and the valve having a larger area than the inlet is subjected to a correspondingly greater force, minus the relief afforded by the reduced outlet of the casing. This greater force on the

valve causes the latter to submerge the float below its normal level, which is presumably falling meanwhile, and the valve opens more widely, thereby increasing the inlet of water to the casing and also increasing the discharge therefrom by increasing the area of the outlet.

In order to adapt the ball cock to service with various pressures, the reduced outlet is provided with means for varying or regulating the flow at that point. The passage for the flow should be approximately in proportion to the pressure in order to insure successful operation of the valve. For example, a high pressure would require a greater relief or less retardation than a low pressure in order to avoid too great a resistance to the action of the valve. If, after having regulated the relief for a high pressure, the ball cock be employed where the pressure is less, there is insufficient retardation and consequently little or no pressure available for opposing the action of the valve. Therefore the capacity of the reduced outlet should be relatively small for a low pressure, and large for a high pressure.

Referring to the drawings forming a part of this specification, in which a plurality of ball cocks are illustrated in forms which vary without departing from the spirit and scope of the invention, — Figure 1 is a longitudinal sectional view of one form of ball cock constructed in accordance with this invention. Fig. 2 is a cross sectional view on the line 2—2 of Fig. 1. Figs. 3 and 4 are respectively longitudinal and cross-sectional views of a different form of the ball cock. Figs. 5, 6, and 7 are longitudinal sectional views of other forms of ball cock. Fig. 8 is a cross-sectional view on the line 8—8 of Fig. 7. Figs. 9 and 10 are respectively longitudinal and cross-sectional views of still another form of ball cock. Figs. 11 and 12 are longitudinal sectional views of different styles of ball cocks having vertically movable valves. Fig. 13 is a cross-sectional view on the line 13—13 of Fig. 12. Fig. 14 is a conventional showing of a complete flush tank in section.

In the illustrated styles of ball cocks, Figs. 1 to 10 inclusive show forms having horizontally movable valves, and Figs. 11, 12 and 13 show forms in which the valves are vertically movable. These styles may be grouped according to other classification. In Figs. 7, 8 and 11 a single discharge outlet is increased and diminished in area by movement of the valve, but in the remaining figures the valve casing has, in each instance, two discharge openings of which one is cut off when the valve is closed upon the inlet.

On the drawings, the same reference characters indicate the same parts wherever they

occur. In the illustrated embodiments of the invention, the ball cocks are adapted for service such as controlling the supply of water for a flush tank, the water being admitted to the tank from a supply pipe in which the water is subjected to a suitable pressure.

The numeral 10 indicates a reservoir in which a supply of water is to be stored.

11 is a flush pipe by which the supply of water is conducted from the reservoir to the point where it is to be used.

12 is a supply or inlet pipe by which water under a suitable pressure is supplied to the reservoir.

13 is a normally open ball cock which controls the inlet of water to the reservoir, by reason of having a ball or float 14 which rises and falls with the level of water in the reservoir and which thereby actuates a valve in the ball-cock casing 15 so as to open and close the inlet. The float 14 is affixed to the free end of the bell-crank lever 16 pivoted at 16^x to ears on the casing. The other end of the lever has suitable sliding connection with a reciprocatory plunger or valve 17. Disregarding at present Figs. 7, 8, 12 and 13, the valve 17 projects through the open end of a valve chamber 18 in the casing 15. The supply pipe 12 is coupled at 19 to the inlet 20 of the casing. The inlet terminates with a valve seat 21 within the valve chamber 18 into which it delivers. The valve carrier 17 has on its inner end a washer or facing 22 which is adapted to engage and close the inlet. The cross-sectional area of the inlet is, in each instance, less than that of the valve, for a purpose hereinafter specified. Water admitted to the valve chamber 18 is subsequently discharged into the reservoir through a discharge nozzle 23 to which it is admitted in a variety of ways.

In Figs. 1 and 2 the valve chamber 18 is surrounded by a discharge chamber 25 with 110 which the nozzle 23 is integrally formed. Communication between the chambers 18 and 25 is by a discharge port 26 which is of less cross-sectional area than the inlet 20. The capacity of the port 26 is regulated 115 by a thumb screw 27. Additional communication between the chambers 18 and 25 is by a plurality of supplemental discharge ports 28 arranged in a circle and extending radially through the wall of the chamber 18. When the valve 17 is held 120 against its seat 21 by the buoyancy of the float 14, it extends across and covers the supplemental ports 28, thus confining the outlet to the relatively small discharge opening 26.

The operation is as follows. When the valve is held against its seat 21, the force exerted against the former by the water pressure is relatively small, but when the 130

valve leaves its seat by reason of a discharge from the reservoir, the valve chamber 18 is filled and discharges through the primary port 26 only a comparatively small proportion of the capacity of the inlet. Consequently the valve chamber becomes a compression chamber, and the valve, being of so much greater cross-sectional area than the inlet, is subjected to an increased force opposing the buoyancy of the float. The result is that the valve is moved quickly away from its seat, thereby partially submerging the float and uncovering the supplemental discharge ports 28. The water level in the reservoir presumably continues to fall, thereby effecting through the valve 17 a continuous increase in the discharge from the valve casing. The buoyancy of the float at all times tends to decrease the discharge area through which the water escapes, and, excepting when the valve is almost touching or is leaving its seat, the area of the outlet is kept less than that of the inlet, notwithstanding the fact that both vary. After the inlet is once opened, the pressure of water on the full area of the valve keeps the float submerged below its normal water line until, during the closing of the inlet, the supply is decreased to such a degree that it can escape without creating a back pressure in the valve chamber. When opposition to the buoyancy of the float is thus relieved, the latter seeks its normal position of displacement, but it never quite reaches that position because, if the screw regulator 27 is correctly adjusted, the valve 17 reaches its seat before the float can reach its normal position. There is, therefore, an excess of buoyancy of the float which keeps the valve firmly against its seat, and in that position the water pressure operates on the smaller portion of the differential area.

The ball cock illustrated in Figs. 3 and 4 has a chamber 30 instead of the annular chamber 25 of Fig. 1. It also has a different arrangement of the port 26 and regulating screw 27, and a single large supplemental port 31 in place of the ports 28. The web 32 in Fig. 1 causes an ejection by the main discharge of water of whatever water leaks around the valve 17.

In the form shown by Fig. 5, the primary discharge opening is a port 33 in the valve 17, communicating with a chamber 34 within the valve. Egress from the chamber 34 is through a port 35 communicating with the nozzle 23. The supplemental opening is indicated at 36, and, as is the case in the forms of Figs. 1 and 3, is covered or closed by the forward end of the valve when the latter is upon the inlet seat. In this form, the screw regulator 27 is necessarily carried by the valve 17 so as to move with the primary opening 33 which it regulates.

is an annular groove in the periphery of the valve for draining off the water which may leak around the valve. The drainage passes into the discharge nozzle with the main body of discharged water.

In the form shown in Fig. 6, the valve 17 and supplemental discharge opening to the nozzle 23 are practically the same as those described. The primary discharge opening, however, is by means of a pipe 38 connected with the chamber 18 and leading to the lower part of the reservoir 10 below the standard water level. The regulator for this primary discharge is a cap 39 screw-threaded over the lower end of the pipe 38. The cap has apertures 40 for the escape of the water, and a tapered seat 41 for projecting into the end of the pipe. The capacity of this end of the pipe for discharging may be varied by turning the cap about the screw-threaded portion. 42 is a valve-stem extending into the inlet 20 for keeping the valve in alignment with its path of movement. The stem has a tapered portion 43 which operates with the perpendicular face of the valve to vary the supply from the inlet 20.

Figs. 7 and 8 show a radically different form as far as appearance and construction are concerned but the result attained by it is the same as the others. In this form the valve chamber 18 and discharge nozzle 23 move with the valve 17. The said chamber and nozzle are formed integrally with a casing 44 which slides upon the exterior of the inlet pipe 20. The latter is mounted in a bracket 45 affixed to the wall of the reservoir, and has one or more lugs 46 which are drawn up against one side of the bracket by a screw-threaded nut 47 on the opposite side of the bracket. The casing 44 has an extension 48 which also slides on the inlet pipe 20 to afford a better bearing to keep the casing steady. Lugs 49 49 on the extension 48 are engaged by slotted arms 50 50 of the bell crank to which the float is affixed. The exterior of the inlet pipe 20 tapers abruptly toward the valve seat 21, and with it an annual shoulder 51 is adapted to coöperate. The said shoulder is formed within the casing 44 between the chamber 18 and the discharge chamber 25. The valve 17 is in the form of a plug screw-threaded in the end of the casing 44 and therefore adjustable relatively to the shoulder 51. It is preferably adjusted so as to seat before permitting the shoulder 51 to engage the inlet pipe. In this form the wall of the chamber 18 operates as the greater portion of the differential area upon which the water pressure acts. As the valve 17 is moved toward the inlet seat to diminish the supply, the shoulder 51 approaches the tapered end of the inlet pipe thereby reducing the area through

which the water escapes to the discharge nozzle.

Referring to Figs. 9 and 10, the chief variation between that form and those of Figs. 1, 3 and 6 lies in the primary discharge outlet. The latter is above the valve chamber and terminates in the wall thereof directly above the nozzle 23. Communication between the primary outlet and the nozzle is by the way of a port 60 extending through the valve from top to bottom. When the valve is retracted from the inlet to its full extent, the forward end of the former uncovers the entrance to the nozzle, and the latter then becomes the supplemental outlet with a full opening. At this position, the port 60 is out of alinement with the primary outlet 22, the latter being unnecessary and in fact cut off.

The form shown in Fig. 11 is similar to that in Fig. 7, in that it has a single discharge outlet which is increased as the valve leaves the inlet seat and which is diminished as the valve approaches the seat. The valve in this form is vertically movable in the valve chamber 18 from which the water discharges through a neck 61 leading to the nozzle 23. The inlet valve seat 62 surrounds the neck 61 thereby providing an annular space through which the supply enters the chamber 18. The capacity of the neck 61 to permit a discharge is varied by a tube 63 affixed to the valve 17 and having a flared end 64. The end 64 has a sliding fit within the nozzle 23, and the portion between it and the valve is reduced as at 65. A tapered portion 66 adjacent the valve is slightly smaller than the neck, thereby providing a narrow annular space for the escape of water from the chamber into the neck. The tube 65 is provided with a plurality of apertures 67 through which the discharge passes from the exterior to the interior thereof and thence through the flared end 64. When the valve 17 is farthest from its seat, the annular inlet admits a greater quantity of water than the apertures 67 can discharge and so a back pressure is created in the chamber. As the valve approaches its seat, the tapered shoulder 66 enters the neck 61, thereby reducing the discharge area at that point and prolonging the back pressure, but, when the inlet is cut down to such a point that the supply can readily escape past the tapered shoulder, the back pressure is relieved and the valve quickly seats. In case some of the water leaks by the valve 17, it enters a groove 68 in the periphery thereof and flows thence through radial apertures 69 to a central aperture 70 and then through the tube 65.

The form illustrated in Figs. 12 and 13 is similar to that of Fig. 11 with respect to the annular inlet, the neck 61, the annular outlet, and the vertically movable valve 17 with

tapered shoulder 66 for varying the area of the outlet. In this form, the valve 17 is attached to a diaphragm 75 inclosing the valve chamber 18, and the latter has, in addition to the discharge neck 61, a continually open discharge outlet 76 with a screw regulator 27. The action of the valve is, in this form, the same as the described action of the form in Fig. 11, with the capacity of being adjusted by the regulator to operate successfully under various pressures of the inlet.

In all the forms herein shown, the provision of a regulator for controlling the discharge from the valve casing enables the pressure of water within the valve chamber to retard the closing of the valve, and so to maintain an excess of buoyancy of the float. The advantage of the latter has already been explained, but, in addition to its value in closing the valve as it does, it prevents the valve from "hammering" when the water pressure fluctuates, as it does when an outlet at some other point in the supply main is suddenly shut off.

The fact that the valve in the present invention presents to the water pressure a relatively small area when closed and a relatively large area when open, makes it in every case more difficult to close the inlet when once open. Ball-cock valves, in which there is nothing of this kind, invariably close with an irregular movement. In such valves the buoyancy of the float tends to exact a force just sufficient to balance the opposing force of the inlet, but, inasmuch as the latter is constantly varied by the closing of the valve, one force or the other is liable to gain on the other temporarily. The result is that the valve closes either with a step-by-step or a see-saw movement. This balancing or fluctuating movement of the valve is prevented in the present invention by the retardation imposed on the float by the pressure against the relatively large valve area.

It is apparent that the invention is capable of still other forms in which the discharge from the valve casing may be controlled, so as to vary with the inlet and still remain less within a certain range.

Having thus explained the nature of my said invention, and described a way of making and using the same, although without attempting to set forth all of the forms in which it may be made, or all of the modes of its use, what I claim is:

1. A ball cock having a valve chamber, a supply inlet therefor, a valve in the chamber of greater cross-sectional area than the inlet, movable toward and from the inlet to close the same, a discharge outlet of less cross-sectional area than the inlet communicating with the valve chamber, and means for varying the pressure in the valve chamber.

2. A ball cock having a valve chamber, a supply inlet therefor, a valve in the chamber of greater cross-sectional area than the inlet, movable to and from and in alinement with the inlet, a discharge outlet of less capacity than the inlet communicating with the chamber, and means for varying the pressure in the valve chamber. 70
3. A ball cock having a valve chamber, a supply inlet therefor, a valve in the chamber of greater cross-sectional area than the inlet, movable toward and from the inlet to close the same, a discharge outlet of less maximum capacity than the inlet communicating with the valve chamber, and means for regulating the capacity of the outlet. 75
4. A ball cock having a valve chamber, a supply inlet therefor, a compression valve in the valve chamber of greater cross-sectional area than the inlet, movable to close the inlet against the supply, a discharge outlet of less capacity than the inlet communicating with the valve chamber and adapted to be diminished when the valve is against its seat and increased when the valve is relatively distant from its seat. 80
5. A ball cock having a valve chamber, a supply inlet therefor, a discharge port of less capacity than the inlet communicating with the chamber, and a compression valve in the chamber movable to and from the inlet and thereby adapted to increase and diminish the discharge outlet. 85
6. A ball cock having a valve chamber, an inlet, a variable outlet, both communicating with the chamber, and means for varying the flow through the inlet and the outlet, substantially as set forth. 90
7. A ball cock having a valve chamber, an inlet, a variable outlet, both communicating with the chamber, and a single valve movable in the chamber for varying the flow through the inlet and outlet, substantially as set forth. 100
8. A ball cock having a valve chamber, an inlet, a variable outlet both communicating with the chamber, and a single valve of greater cross-sectional area than the inlet, movable in the chamber for varying the flow through the inlet and outlet, substantially as set forth. 105
9. The combination with a reservoir for fluid and a float therein, of a supply pipe for fluid under pressure, a valve casing, a valve in the casing connected to the float so as to move therewith, an inlet for admitting fluid from the supply pipe to the casing, and an outlet for the escape of fluid from the casing, said inlet and outlet being so arranged and of such a character as to be controlled by the valve and to afford, when open, variable passages, of which the inlet is always greater than the outlet, until the inlet is nearly closed. 115
10. A ball cock having a valve chamber, an inlet, a variable outlet, both communicating with the chamber, and a single valve in the chamber movable to and from the inlet, said inlet and outlet being so arranged that movement of the valve toward the inlet decreases the outlet and movement from the inlet increases the outlet. 120
11. A ball cock having a valve chamber, an inlet thereto, a variable outlet for conducting water from the chamber to a reservoir, and an inlet valve in the chamber of greater cross-sectional area than the inlet and actuated by a float in the reservoir, said outlet being so arranged as to be increased or diminished by the valve. 125
12. The combination with a reservoir and a supply pipe for conducting fluid under pressure, of a valve casing, an inlet for the fluid, a float in the reservoir, an inlet valve of greater area than the inlet, connected to the float so as to be actuated thereby to close the inlet when the float rises, and an outlet communicating with the casing so as to be varied by the valve therein and kept less than the inlet when the valve is away from the latter. 130
13. The combination with a supply pipe for conducting fluid under pressure, a reservoir for fluid, and a float in the reservoir, of a valve casing, an inlet for conducting fluid from the supply pipe into the valve casing, an inlet valve in the casing of greater area than the inlet, and connected to the float so as to move to and from the inlet as the float rises and falls, and a discharge outlet communicating with the casing so as to be increased when the valve recedes from the inlet, and diminished when the valve approaches the inlet, said outlet being less than the inlet while the latter is wide open, and until it is nearly closed by the valve. 140
14. The combination with a supply pipe for conducting fluid under pressure, a reservoir for fluid, and a float in the reservoir, of a valve casing, an inlet for conducting fluid from the supply pipe into the valve casing, an outlet communicating with the casing, and a valve in the casing of greater area than the inlet, and connected to the float so as to be actuated thereby, and adapted to control the inlet and outlet so that the latter is always less than the former except when the former is nearly closed. 145
15. A float valve comprising a float, a valve chamber, a water inlet into said chamber forming a valve seat, an outlet from said chamber of less capacity than the inlet, a valve in said chamber and a connection between the valve and the float, said valve having a greater area than the area of the inlet, so that the back pressure caused by the small outlet and the great area of the valve, is sufficient to hold the valve from its seat until the float is submerged to a greater extent than it would be 150

by the normal pressure of the water in the inlet, means being provided for varying the pressure in the valve chamber.

16. A ball cock having a valve chamber and an inlet, a valve of greater cross sectional area than the inlet, and an outlet of less capacity than the inlet formed by the surfaces of the valve chamber and the valve.

17. A ball cock having a valve chamber and an inlet, a valve of greater cross sectional area than the inlet, an outlet of less capacity than the inlet formed by the surfaces of the valve chamber and the valve, and means for varying the pressure in the valve chamber.

18. A ball cock having a valve chamber provided with inlet and outlet passages, a float operated valve, means in the chamber for effecting a variable pressure resistant to the closing of the valve, and means for relieving said pressure when the valve is relatively near its seat.

19. A ball cock having a valve chamber provided with inlet and outlet passages, a float operated valve, and means between the inlet and outlet passages for retarding the

flow, said means being adapted to vary the degree of retardation.

20. A ball cock having a valve chamber provided with inlet and outlet passages, a float operated valve, and means coöperating with the flow between the inlet and outlet of the valve chamber for developing resistance to the closing of the valve, said means being adapted to vary the degree of resistance.

21. A ball cock having a valve chamber provided with inlet and outlet passages, an inlet valve adapted to close the inlet in the direction opposite to the flow, means movable with the valve for retarding the flow between the inlet and outlet, a float, and means operable by the float for moving the valve, said means being adapted to vary the ratio of force and movement imparted to the valve.

In testimony whereof I have affixed my signature, in presence of two witnesses.
